UNITED STATES PATENT OFFICE

WILSON W. BURSON, OF ROCKFORD, ILLINOIS

KNITTING MACHINE

Application filed May 25, 1925. Serial No. 32,593.

This invention relates in general to knitting machines, and has more particular reference to knitting machines of the flat bed type.

The principal object of the invention is to provide a knitting machine having a needle operating cam or a knitting element which actuates the needles but once during a reciprocation and provides knitting movement at a desired instant. In devices of this character provided heretofore, it has been the common practice to provide a single cam having a portion at each end adapted to bring the needles down to knitting position and, thus in passing across the bed in either direction, the needles are first retracted to knitting position by the cam without purpose, then raised to yarn receiving position, and again retracted to knit the yarn received. The first and unnecessary retracting movement seriously affects the operation of the machine, for in retracting the needles having a loop of yarn formed thereover, the yarn which extends to form many other loops on either side, is given an undue strain and frequently breaks for this reason. This breakage occurs more frequently when attempts are made to knit a fabric having a relatively fine texture, the fineness of the weave being determined by the size of the needles employed.

Another important object of the invention is to provide in a knitting machine a needle actuating cam having a minimum wearing surface and which will not disturb the loops previously knit except during the next succeeding knitting operation, thus substantially eliminating yarn breakage and permitting the use of a finer or more delicate yarn in knitting.

Numerous other objects and advantages of the invention will be apparent as it is better understood from the following description, which, taken in connection with the accompanying drawings, discloses a preferred embodiment thereof.

Referring to the drawings:

Figure 1 is a side elevation having parts thereof broken away, of a knitting machine embodying my invention;

Fig. 2 is a detailed plan view showing a portion of a cam slide embodying my invention;

Fig. 3 is a side elevation of the slide shown in Fig. 2;

Fig. 4 is a bottom plan of the slide shown in Fig. 2;

Fig. 5 is a section taken substantially on line 5—5 of Fig. 2;

Fig. 6 is a section taken substantially on line 6—6 of Fig. 3;

Fig. 7 is similar to Fig. 3 and shows a side elevation of the slide with parts in a different relative position;

Figs. 8, 9 and 10 are fragmentary details illustrating changes in position of parts of the cam-controlling mechanism; and

Fig. 11 is an enlarged detail view of the cam-controlling mechanism.

For the purpose of illustrating my invention, I have shown on the drawings a knitting machine of the type and character of those shown in my earlier U. S. Patents No. 944,011, issued December 21, 1909; No. 944,012, issued December 21, 1909; No.

996,059, issued June 27, 1911; No. 1,025,182, issued May 7, 1912; No. 1,201,691, issued October 17, 1916, and No. 1,531,272, issued March 31, 1925, to the B. Z. D. Knitting Co., of Rockford, Illinois. The frame 11 provides a support for the various mechanisms of the machine which include a power shaft 12 having a pulley or other suitable power transmitting element 13 secured thereto and adapted to drive the machine, a needle bed 14, needle jacks 15 and a pattern member 16 for controlling the needle jacks to determine the needles that will knit upon the next succeeding reciprocation of a cam slide 17, as will be later described. The pattern member 16 is mounted on a shaft 18 and is progressively rotated by the gear 19 to vary the width of the garment being knit, the gear 19 being in turn driven by suitable mechanism from the power shaft 12, and controlled by a control mechanism 21. The cam slide 17 is secured to a cross-head 22 and is reciprocated thereby. The cross-head 22 is mounted on guides 23 and carries a pivoted lever 24, which is connected at 25 to a link 26 having a bearing at 27 upon a bed plate 28 of the

70

75

80

85

90

95

100

frame 11; a link 29 is secured to the lever 24 at 31 and to a gear 32 by a crank pin 33. Rotation of the gear 32 through the crank pin 33 causes the link 29 to reciprocate, which in turn reciprocates the cross-head 22 in timed relation with the pattern member 16 and the other elements of the machine. All of the elements just described and the operation thereof, are described and shown in detail in my above-mentioned prior 10 patents.

At the forward end of the cam slide 17, edges 34 are confined in guideways in the needle bed and a pivot plate 35 is secured by a pivot pin 36 to a bracket 37, which is in turn secured to the forward end of the slide by screws 38. A cam 41 (Fig. 4) and a pivot cam 42 are secured to the pivot plate 35 and extend through an opening 43 in the slide 17 to engage the needle jacks. A spring 44 which is positioned in a housing 45 suitably secured to the pivot plate 35 extends through the pivot plate and has a bearing against the slide 17. This spring normally tends to hold the pivot plate 35 in elevated position or to hold the cams 41 and 42 out of jack engaging position. The cams travel normally above the nibs of the jacks and are projected into position to engage the jacks on an active knitting stroke by moving down the pivot plate 35 against the spring 44. This downward movement is provided for by a four-toothed wheel 46 carried by the cam slide 17 and located at one side of the pivot plate 35. This wheel is adapted to engage an end 47 of a bracket 48 which is secured to the pivot plate 35 (Figs. 2, 3 and 6). The end 47 extends out into position to be depressed by a tooth of the wheel 46 or to be elevated between the teeth by the upward pressure of the spring 44. A ratchet wheel 49 is fixed with the toothed wheel 46 and is adapted for engagement with pawls 78 secured to the frame upon passing thereover to move the toothed wheel into the position shown, or either way from the position shown preferably to the extent of 45 degrees at each movement. The position shown in Fig. 3 of the drawings is that in which the cams 41 and 42 are in jack-engaging position and the movement of the wheel 46 through an angle of 45 degrees in either direction from the position shown permits the pivot plate to rise and lifts the cams from jack engaging position, as shown in Fig. 7. A further movement of 45 degrees in either direction will bring the cams back into jack engaging position. The four-toothed wheel 46 and the ratchet wheel 49 are rotatably mounted on a shoulder stud 51 which is secured in a bracket 52 secured to the slide 17. The ratchet wheel and the four-toothed wheel 46 are rotated by means of a pawl 78, conveniently mounted in the needle bed 14 and arranged to engage and actuate the toothed wheel 49. A

pawl is mounted at each end of the needle bed on each side of the machine and in a position such that the toothed wheel 49 passes and engages the tip of each pawl once during each reciprocation of the slide 17. In Figs. 8, 9 and 10, the operation of the wheel and a pawl is illustrated, and it will be noted that each pawl is adapted to actuate the ratchet wheel when the latter is traveling in one direction only. When the ratchet wheel is moving to the right, as indicated by the arrow in Fig. 8, the pawl tip engages the lowermost tooth of the wheel 49 and moves the wheel to the position shown in Fig. 9, in which position the pawl passes beneath the tooth and disengages from the wheel. When the ratchet wheel moves toward the left, as indicated by the arrow in Fig. 10, the tip of the pawl engages a tooth of the ratchet wheel and is depressed against the needle bed so that the ratchet wheel may pass freely and without being turned by the pawl. The ratchet wheel 49 is provided with eight teeth, so that each time the ratchet wheel 49 engages a pawl, it is turned through an arc of 45 degrees. In other words, each time the slide reciprocates past a pawl 78, the wheel 46 is moved through an angle of 45 degrees and the cams are moved into or out of jack-engaging position. Since a pawl is mounted at each end of the needle bed and is arranged to engage the wheel 49 at the beginning of a reciprocation of the slide 17, it is possible to move the wheel through 45 degrees at the beginning of each reciprocation, and the cams may be either lowered into jack-engaging position or lifted out of jack-engaging position at the beginning of any knitting stroke of the cross head of the machine. If it is desired to have the cams 41 and 42 remain in cam-engaging position during consecutive knitting strokes, the pawl or pawls may be rotated out of wheel-engaging position by means of the mechanism shown in Fig. 11 of the drawings.

The pawls are mounted in position upon a shaft 79, which extends through a part 81 of the needle bed 14 and which carries a lever 82 at its opposite end, the shaft being rotatably mounted in the needle bed and a spring 83 being attached to the needle bed and arranged to engage an end of the lever 82 in order to urge the pawl 78 normally into a ratchet-wheel engaging position.

A sleeve 84, having oppositely protruding lugs 85 and 86, is pivotally mounted upon the needle bed part 81. The lug 85 is arranged to engage the lever 82 and to depress the pawl 78 from wheel-engaging position upon rotation of the sleeve 84. A lever 88, which is preferably formed of sheet metal, is pivoted on a rod 89, suitably mounted in the needle bed, and has a cam following tooth portion 91 at one end. The opposite end of the lever 88 engages the lug 86 of the

sleeve 85. The tooth portion 91 of the lever 88 is disposed to engage the periphery of a cam disc or wheel 92 and to be moved thereby about the rod 89. A spring 93 is arranged 5 between the lever 88 and a portion of the needle bed to urge the tooth portion 91 into engagement with the cam disc. The cam disc or wheel 92 is attached to the end of the pattern member or wheel 16 and is thus arranged to actuate the lever 88 at various intervals during the rotation of the pattern wheel. The periphery of the cam disc 92 is formed to provide toothed portions and recesses. When the toothed portion of the 10 lever 88 engages a toothed portion of the cam disk, the lever is rotated in a counter-clockwise direction, viewing Fig. 11, against the tension of the spring 93, and engages the lug 86, causing the sleeve 84 to rotate, and the lug 85, in turn, moves the lever 82 against the tension of the spring 83, and hence rotates 15 the pawl 78 out of normal wheel-engaging position. When the toothed portion 91 engages a cam recess, the pawl has a normal wheel-engaging position.

The cams 41 and 42 and the mechanism for the control thereof will now be described. The cam 41 is or may be formed of sheet metal of suitable hardness and is or may be spaced 20 away from the pivot plate 35 by a spacing plate 53 of sufficient thickness to bring the cam 41 into engagement with the nibs of the needle jacks when the pivot plate is in the lower position. The pivot cam 42 is pivoted 25 to the plate by a shoulder screw 54 and is provided at each end with a cam portion 55. These cam portions are positioned one askew to the other (Fig. 5) to facilitate the engagement of the jack nibs by one or the other thereof, which is determined by the position of the cam 42. The cam 42 is moved to present one or the other of the cam portions 55 into jack 30 engaging position and is locked in this position by a slide 56 having cam portions 57 and 58 engaging brackets 59 and 61 secured to the cam 42 as best shown in Figs. 2 and 3. The slide 56 is attached by a link 62 to a bell crank 63 pivotally secured to a bracket 64, which is in turn secured to the pivot plate 35. A screw 65 providing a pivot for the bell crank 63 is preferably of sufficient length to provide space for a spring 66 and a washer 67 which are provided to impose friction on the bell crank 63 which may be controlled by the screw 65. A pin 68 is provided in the bell 45 crank and adapted to engage brackets 69 and 71 which may be secured to any suitable portion of the frame of a knitting machine, and preferably at a point that will facilitate the engagement of the pin 68 by one of the brackets 69 or 71 just prior to the end of each reciprocating movement of the slide 17, so that at the end of each reciprocation the pin 68 will be engaged and will oscillate the cam 42, raising first one cam portion 55 and then

the other out of operative position. By moving the slide 56 to the right (Fig. 3), the bracket 59 secured to the cam 42 is wedged upward by the cam portion 57 and the bracket 61 is permitted to lower by the cam portion 58 to a top horizontal surface 72 of the slide 56, at which time the bracket 59 will be disposed on the top horizontal surface 70 of the cam portion 57. It will be noted that this is a reversal of the position shown in Fig. 3, 75 and that a reversal of the slide brings the cam 42 back to the position shown. The cam portions 55 are each provided with a projection 73 and a recess 74 opposite the projection (Fig. 4) for effecting knitting movement of 80 the needles. The pivot cam 42 is preferably pivoted to the pivot plate above the cam 41 and arranged so that when either of the cam portions 55 are in operative position, they are in alignment with a portion of the cam 41 85 to facilitate continuous movement of the needle upon the passing of the cams through the needle jack nibs. Upon movement to the right of the slide 17, the pivot cam 42 is oscillated so that the right hand cam portion 90 55 is raised out of operative nib-engaging position and the left hand cam portion 55 is lowered into nib-engaging position so that a cam surface 75 of the cam 41 first engages the forward nibs of the needle jacks and 95 brings the needles forward into yarn-receiving position. A cam surface 76 next engages the rearward nibs of the needle jacks to retract the needle with the yarn and brings the nibs of the needle jacks into position for 100 engagement with a surface 77 of the left hand cam portion 55 of the pivot cam 42. This cam portion, by means of the projection 73 and recess 74, then effects the knitting movement and passes from engagement with the 105 nibs, leaving them in position to be engaged by the cam 41 upon its return stroke, when a similar operation is performed, except that the cam portion 55, to the right in Fig. 5, effects the knitting movement, the pivot cam 110 having again been oscillated so that the cam portion to the left is in raised position and does not affect the jacks. By this arrangement, all unnecessary movements of the needle jacks and the resulting yarn strains are 115 eliminated, as well as unnecessary wear of the parts. A lighter yarn may be used which may be more closely knitted to produce a finer fabric.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a knitting machine, the combination of a needle bed having knitting needles mounted therein, jacks for operating said needles, a cam for projecting and retracting said jacks, and a follower cam for effecting knitting movement of said needle jacks.
2. In a knitting machine, the combination of a needle bed having knitting needles mounted therein, jacks for operating said needles, a cam for projecting and retracting said jacks, and a follower cam for effecting knitting movement of said needle jacks, said cams being secured together and adapted to reciprocate across the needle bed.
3. In a knitting machine, the combination of a needle bed having knitting needles and jacks for controlling said needles mounted therein, a reciprocating cam for actuating said jacks to project the needles to yarn receiving position and to retract the needles with the yarn to a predetermined knitting position, and a knitting cam for engaging the jacks after said retraction to effect knitting movement of said needles.
4. In a knitting machine, the combination of a needle bed having knitting needles and jacks for controlling said needles mounted therein, a reciprocating cam for actuating said jacks to project the needles to yarn receiving position and then to retract the needles with the yarn a predetermined distance, and a pivoted knitting cam for engaging the jacks to effect knitting movement of said needles, said cams being mounted on a reciprocating slide member and arranged to engage the needle jacks successively during the reciprocating of the slide member, said pivoted cam having cam surfaces adapted alternately to have jack-engaging position during successive reciprocations of said slide.
5. In a knitting machine, the combination of a needle bed having knitting needles and jacks for controlling said needles mounted therein, a reciprocating cam for engaging said jacks to project the needles to yarn receiving position and to then retract the needles with the yarn to a predetermined knitting position, and a pivoted knitting cam having surfaces adapted to engage the jacks when in knitting position to effect knitting movement of said needles, said cams being secured to a reciprocating member in overlapping relation to facilitate continuous movement of the jacks in passing therethrough.
6. In a knitting machine, the combination of a needle bed having knitting needles and jacks for controlling said needles mounted therein, a reciprocating cam slide, a cam secured to said reciprocating cam slide for engaging said jacks to project the needles to a yarn-receiving position and to then retract the needles with the yarn to a predetermined knitting position, and a follower cam pivoted to said reciprocating cam slide and hav-

ing jack-engaging portions alternately disposable in jack-engaging position during successive reciprocations of said slide, said portions being disposed adjacent opposite ends of said needle-projecting and retracting cam to effect knitting movement of the needles when in jack-engaging position. 70

7. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn to a predetermined knitting position, and a follower cam pivoted to said reciprocating cam slide and having portions arranged to engage the needle jacks alternately at opposite ends of said first mentioned cam for effecting knitting movement of the needles when the same have been retracted by said first-mentioned cam to knitting position. 80

8. In a knitting machine, the combination of a needle bed having knitting needles and jacks for controlling said needles mounted therein, a reciprocating cam slide, a cam secured to said reciprocating cam slide and arranged to actuate said jacks successively during a reciprocation of a slide in either direction in order to project the needles to yarn-receiving position and to retract the needles with the yarn a predetermined distance to a knitting position, and a follower cam pivoted to said reciprocating cam slide and having portions adapted to engage said jacks after said first mentioned cam has retracted said needles when the cam is traveling in either direction in order to effect knitting movement of the needles, said first mentioned cam and said follower cam together being adapted to effect continuous movement of the knitting jacks in passing therethrough in either direction. 95

9. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn a predetermined distance, a follower cam pivoted to said reciprocating cam slide and having portions arranged to engage the needle jacks at either end of said first mentioned cam to effect knitting movement 100 of the needles, and means for controlling said follower cam. 110

10. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn a predetermined distance, a follow- 125

er cam pivoted to said reciprocating cam slide for engaging the needle jacks at either end of said first mentioned cam for effecting knitting movement of the needles, said follower cam having a jack engaging portion at each end, either of which may be disposed in jack engaging position, and means for actuating said follower cam to dispose said jack-engaging portions alternately in jack-engaging position during successive reciprocations of said cam slide.

11. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn a predetermined distance, a follower cam pivoted to said reciprocating cam slide for engaging the needle jacks at either end of said first mentioned cam for effecting knitting movement of the needles, said follower cam having a jack engaging portion at each end, a reciprocating wedge member for controlling said follower cam to dispose the jack engaging portions in jack-engaging positions.

12. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn a predetermined distance, a follower cam pivoted to said reciprocating cam slide for engaging the needle jacks at either end of said first mentioned cam for effecting knitting movement of the needles, said follower cam having a jack engaging portion at each end, either of which may be disposed in jack engaging position, and means for controlling said follower cam to engage the jacks at either end of said first mentioned cam, said means comprising, a slide having wedge portions engaging said follower cam on either side of the pivot thereof, and means for actuating said slide.

13. In a knitting machine, the combination of a needle bed having knitting needles and jacks for controlling said needles mounted therein, a reciprocating cam slide, a cam secured to said reciprocating cam slide for engaging said jacks to project the needles to receive yarn and to retract the needles with the yarn a predetermined distance, a follower cam pivoted to said reciprocating cam slide for engaging the needle jacks at either end of said first mentioned cam for effecting knitting movement of the needles, said follower cam having a jack engaging portion at each end, adapted for disposal in jack engaging position, and means for controlling said follower cam to dispose said cam alter-

nately in jack-engaging position opposite the ends of said first mentioned cam, said means, comprising, a slide having wedge portions engaging said follower cam on either side of the pivot thereof to move said follower cam to bring either end thereof into jack engaging position and lock the follower cam in said position, and means for actuating said slide.

14. In a knitting machine, the combination of a needle bed having knitting needles and jacks for controlling said needles mounted therein, a reciprocating cam slide, a cam secured to said reciprocating cam slide for engaging said jacks to project the needles to a yarn receiving position and to retract the needles with the yarn to a predetermined distance knitting position, a follower cam pivoted to said reciprocating cam slide for engaging the needle jacks at either end of said first mentioned cam for effecting knitting movement of the needles, said follower cam having a jack engaging portion at each end, either of which may be disposed in jack engaging position, and means for controlling said follower cam to engage the jacks at either end of said first mentioned cam, said means, comprising, a slide mounted on said reciprocating cam slide and having wedge portions engaging said follower cam on either side thereof and arranged to move either end of said follower cam into jack engaging position and lock the follower cam in said position, and means mounted on said cam slide for actuating said slide and adapted to engage a bracket secured to the knitting machine frame.

15. In a knitting machine, the combination of a needle bed, knitting needles mounted in said bed, jacks for operating said needles arranged in said bed, a cam for projecting and retracting said jacks, and a pivoted knitting cam having surfaces disposable in cam-engaging position adjacent opposite ends of said jack actuating cam for effecting knitting movement of said needle jacks, said cams being secured upon a slide and adapted to reciprocate across the needle bed, whereby said pivoted cam is made operable on alternate strokes of said slide.

16. In a knitting machine, the combination of a needle bed having knitting needles and jacks for controlling said knitting needles mounted therein, a reciprocating cam for actuating said jacks to project the needles to yarn-receiving position and then to retract the needles with the yarn to a predetermined knitting position, and a pivoted knitting cam for engaging the jacks in said knitting position, said cams being mounted upon a slide and adapted to reciprocate across the needle bed, said pivoted cam having portions alternately disposable in jack-engaging position during alternating reciprocation of said slide.

17. In a knitting machine, the combina-

tion of a needle bed, knitting needles and jacks for controlling said needles mounted in said needle bed, a reciprocating cam for actuating said jacks to project said needles to a yarn-receiving position and thence to retract said needles to a predetermined knitting position, a pivoted knitting cam for engaging the jacks in said knitting position to effect knitting movement of said needles, 10 said cams being mounted upon a pivot member carried by a reciprocating slide, said cams being normally supported out of jack-engaging position, and means for depressing said pivot member to bring said cams into 15 jack-engaging position during a reciprocation of said slide.
